FIG. 1.

FIG. 2.

FIG. 3.

INVENTOR:

JEANNETTE L. LEBENS

BY Alfred Wetcher
ATTORNEY.

UNITED STATES PATENT OFFICE

144,397

DESIGN FOR A THIMBLE

Jeannette L. Lebенs, University City, Mo.

Application May 30, 1945, Serial No. 119,810

Term of patent 3½ years

(Cl. D3—19)

To all whom it may concern:

Be it known that I, Jeannette L. Lebенs, a citizen of the United States, residing at University City, county of St. Louis, State of Missouri, have invented a new, original, and ornamental Design for a Thimble, of which the following is a specification, reference being made to the accompanying drawing, forming a part thereof, in which Figure 1 is a top plan view of a thimble showing my new design; Figure 2 is a front elevational view thereof; and Figure 3 is a side elevational view thereof.

I claim:

The ornamental design for a thimble, substantially as shown.

JEANNETTE L. LEBENS.
